COMBINED LIGHTING FIXTURE AND COVER
FOR A CEILING HEATER AND VENTILATOR
COMBINATION

George D. Hart, Cincinnati, Ohio, assignor to Nutone,
Inc., Cincinnati, Ohio, a corporation of New York

Filed Mar. 30, 1960, Ser. No. 59,961

Term of patent 14 years

(Cl. D81—10)

I claim:

The ornamental design for a combined lighting fixture and cover for a ceiling heater and ventilator combination, substantially as shown.
